UNITED STATES PATENT OFFICE.

THOMAS G. HAWKES, OF CORNING, NEW YORK.

DESIGN FOR A GLASS VESSEL.

SPECIFICATION forming part of Design No. 25,944, dated August 18, 1896.

Application filed July 10, 1896. Serial No. 598,757. Term of patent 14 years.

To all whom it may concern:

Be it known that I, THOMAS G. HAWKES, a citizen of the United States, and a resident of Corning, in the county of Steuben and State 5 of New York, have invented and produced a new and original Design for a Glass Vessel or Dish, of which the following is a specification, reference being had to the accompanying drawings, forming part thereof, in which—
10 Figure I is a bottom view of a glass vessel or dish, showing my design. Fig. II is an axial section thereof.

The leading features of my design consist of three large radial fan figures, approximately circular bands surrounding the fan figures and overlapping, so as to form three radial ovate figures separating the fan figures, and diamond-shaped figures located between the bands, having central rosettes, thus forming 15 what I call the "Nautilus" design.

Three large radial fan figures surrounded by approximately circular bands are located on the body of the dish. Three radial ovate figures are produced by the overlapping of the adjacent portions of the circular bands. 25 Between the bands are located diamond-shaped figures having rosettes centrally arranged.

Having thus described my invention, the following is what I claim as new therein and 30 desire to secure by Design Letters Patent:

The design for a glass vessel or dish substantially as herein shown and described.

THOMAS G. HAWKES.
